ELECTRIC PICK-UP

Application filed September 20, 1929. Serial No. 383,920.

The present invention relates to electric pickups for use with phonograph records and the like, adapted to generate electric currents in accordance with the vibratory movements of a stylus traveling in the record groove.

The present invention contemplates an electric pickup provided with a current generating coil, stationary magnet system and vibratory stylus and operative parts so arranged that the form of the current wave generated thereby will reproduce with excellent fidelity, the form of the record groove by which the stylus is operated.

15 The present invention contemplates an improved electric pickup having excellent tracking qualities and desired fidelity over a wide range of frequencies so that the pickup will reproduce not only the low notes but 20 the extremely high notes as well as intermediate notes, without distortion.

The invention also contemplates the design of an electric pickup wherein the current generating coil is wound about a core 25 normally receiving substantially no magnetic flux but which does receive a flux varying according to the movement of the stylus, whereby all the flux variations in the core take place at comparatively low intensity, thereby avoiding the effects of saturation; 30 present where the magnet system employs a more or less saturated core.

The pickup is accordingly so designed that a vibratory armature in the field of the magnet and outside the coil is caused to disturb the normally balanced flux relation in the core to induce flux therein and thereby generate undulatory currents.

45 The present invention also contemplates the design of an electric pickup in such a manner that the parts may be readily assembled and adjusted and yet be held in position by rugged parts so that there is little likelihood of the device requiring attention once it is adjusted.

The present invention also contemplates an electric pickup wherein adjustable resilient stops offering no appreciable resistance to the vibration of the bar hold the stylus 55 bar in neutral position, so as to prevent its

striking the pole tips or being attracted too close to one of them.

The present application relates to certain improvements over the forms shown in my prior application 153,596, filed December 9, 1926.

60 The accompanying drawings show, for purposes of illustrating the present invention, one embodiment in which the invention may take form, together with several modifications of certain parts, it being understood that the drawings are illustrative of the invention rather than limiting the same.

In the drawings:

Figure 1 is a front view of the pickup, 65 with the cover removed;

Figure 2 is a central section on the line 2-2 of Figure 1;

Figure 3 is an enlarged view taken in the same direction as Figure 1, but showing a 70 slight modification;

Figure 4 is a fragmentary section on the line 4-4 of Figure 2 looking in the direction of the arrow;

Figure 5 is a section on the line 5-5 of 75 Figure 1 looking in the direction of the arrow;

Figure 6 is a side elevational view of the pickup showing it in position over a record;

Figures 7 and 7a are enlarged front and 80 sectional views showing a modified arrangement of vibratory stylus bar and pole pieces;

Figure 8 is a fragmentary view illustrating a modified form of core;

Figure 9 is a view similar to Figure 8 85 showing a still further modified form of core and vibratory armature; and

Figure 10 is a view similar to Figure 3 showing a modified form of resilient stop for the vibratory stylus bar.

90 The electric pickup is mounted on a swinging reproducer support 10 of more or less conventional shape so that the reproducer can move back and forth over the surface of the phonograph or other form of disc record. It will, of course, be understood that the pickup may be mounted on any suitable form of support to have it cooperate with the record grooves of disc or cylinder records or other types of records bearing 100

impressions adapted to actuate a reproducer stylus.

As more clearly shown in Figure 2, the supporting arm 10 is secured to a supporting plate 11, and this plate carries a fixed base or support 12 on which are mounted the magnet, the core, the coil and the vibratory stylus bar as shown in detail in Figures 1 to 5 inclusive.

10 The stylus is indicated at 13. It is clamped in place in a stylus bar 14 by a clamping screw 15. The stylus bar has laterally extending bearing members or pintles indicated at 16 which are provided with ball receiving recesses 16' adapted to receive balls 17. One of the balls 17 is carried in a pocket or recess 18 in the lower part of the support 12, while the other ball is carried in a pocket or recess 19 in an adjustable clamping screw 20 threaded through the stylus bearing support and adapted to be locked in place by a lock nut 21.

15 In the form of construction shown in Figures 1, 2 and 3, the stylus bar 14 extends upwardly above the pivotal axis and carries armature members 22 and 23 of soft iron. The stylus bar is made of a non-magnetic material, preferably of light weight material such as an aluminum alloy. The stylus bar 30 is here shown as being provided with resilient sponge rubber pads 24 covered with thin metal plates 25. Adjusting screws 26 are threaded through the side walls 27 of the support or base 12 and are adjusted against 35 these resilient pads so as to hold the stylus bar in a neutral position and prevent chattering. The adjusting screws 26 may be placed above the pivot, as shown in Fig. 1, or below the pivot, as shown in Fig. 3. They 40 are locked in place by lock nuts 28.

45 The magnet for the pickup is indicated at 30 and is here shown in the form of a horseshoe magnet having poles located at 31 and 32. Pole pieces or tips 33 and 34 are secured on the support 12 by screws indicated at 35. These pole tips are spaced apart to provide a gap slightly greater than the width of the movable armature and are so shaped that the armature projects above the 50 pole tips as will be clear from Figures 1 and 3. The magnet is clamped in place by a bridging strap 36, secured to the support 12 by bolts 37 threaded into a bridge 38 in the supporting base 12.

55 The upper end of the supporting base 12 is provided with a forward extension or bridge 39 and the bridges 38 and 39 are notched as indicated at 40 to receive the stationary soft iron core 41. This core is provided with a short longitudinal slot 42 and is clamped in place by a screw 43 threaded into the forward extension 39. The core 41 carries a coil 44, this coil being preferably a pre-wound coil shaped to fit between the bridging members 38 and 39. The coil is

slipped in place between the bridging members and the core passed through the opening in the coil to secure it in place and is then secured in adjusted position by the screw 43. The coil has leads 45, 46 adapted to be secured to binding posts 47 carried in the upper end of the support 12. These binding posts are connected to wires 48 passing out through the reproducer support 10.

10 The lower end or tip of the core 41 is notched as indicated at 50. The width of this notch is substantially the same as the spacing between the pole tips 33 and 34. The armature members 22 and 23 extend into this notch but do not contact with the tip of the core. The tip of this core is spaced a substantial distance from the pole tips 33 and 34 so that a negligible amount of magnetic flux will be induced in the core, most of the flux passing directly across the air gap and across the armature.

15 In assembling the device, the stylus bar and associated parts are secured in place, the pole tips being mounted on the base. The coil may then be inserted in place and the core secured in position after which the magnet may be slid into place by being passed down alongside the support 12 and secured by the bridging strap 36. The device is closed and covered by a protecting cover 95 plate 52 which may be held in place by nuts 53 threaded onto the ends of the studs 37.

20 In the form of construction shown in Figure 7 and 7a, the vibratory stylus bar 70 is designed to be much shorter than the form shown in Figure 1. Here the needle or stylus 71 is secured in place by a clamping screw 72 above the axis 73 about which the stylus bar vibrates. The stylus bar is provided with armature members 74 carried between pole pieces 75 and 76 similar to the pole pieces 33 and 34. The armature vibrates adjacent to core 77 similar to the core 41. In order to concentrate the magnetic field in the gap, the lower edges of the pole tips 75 and 76 are rounded or beveled as indicated. The adjustable stop screws 78 are similar to the clamp screws 26 but in this figure the resilient connection is in the form of springs 79 which surround pins 79' carried by the stylus bar and which enter recesses 79'' in the support 12'. 100

25 The stylus bar is mounted on ball bearings as indicated, and in both these forms of construction, the pivot is located approximately midway between the needle point and the armature so as to obtain a 1 to 1 relation.

30 In the form of construction shown in Figure 8, the parts may be the same as shown in Figures 1 to 3 except that as here shown the core 81 is cut away to provide a long gap 82 thereby making a somewhat longer path for magnetic flux escaping and leaking from the pole tips into the core. 105

In the form of construction shown in Figure 9, the armature member 91 is indicated as being in the form of a single piece of soft iron suitably secured to the vibratory stylus bar. This single piece of magnetic material being carried midway between the pole tips receives induced magnetism of both poles and has a neutral zone through the middle of its mass. It acts as a two piece 16 armature. Here the pole tips are brought much closer together and the core 92 has a much narrower gap 93.

In the form of construction indicated in Figure 10, the movable stylus bar is of the type shown in Figure 1 and the same reference characters are employed. Instead, however, of having the adjusting screws bear directly on the plates 25 surrounding the sponge rubber pads, additional resilient 20 stops are provided in the form of cups 95 slidably carried in drillings 96 and urged toward the stylus bar by springs 97 held in place by screws 98.

In the various forms of construction herein shown, the stylus bar is adjusted to normally lie substantially centrally between the pole tips and hence the iron armature members carried thereby are substantially equally magnetized and of opposite polarity. In 25 the case of the one piece armature of Figure 9, the opposite halves of this piece act as separate and distinct magnets of equal intensity and opposite polarity. When the armature is in the neutral position, a negligible amount of flux is created lengthwise of the core, but as soon as it is moved in either direction, the flux in the core is 30 redistributed thereby generating a current in the coil which may be amplified and employed in the usual manner.

So far as the ear is able to detect, the devices made with the magnetic arrangement shown in Figures 1, 8 and 9 all operate in substantially the same manner and give 45 excellent reproductions of phonograph records. So far as the ear is concerned there appears to be no difference in the quality of the music or speech produced by either of these arrangements.

The arrangement provided in Figure 7, however, will give better reproductions of higher pitched notes owing to the much smaller mass of moving parts.

In all these forms of construction, it will be noted that the armature is substantially free from restraint. It is able to move without being impeded by stiff springs. The stop means provided offer practically no resistance to the vibration of the armature. As the iron in the coil is operating at exceedingly low density, flux variation will be far more faithful than in forms of construction in which the core is at all times operating under comparatively high flux density.

The placing of the coil and core between the sides of the magnet is a very convenient and compact arrangement and economizes spaces and produces a nice balance over the needle. The position of the magnet relative to the core and coil seems, however, to have little effect on the quality of the reproduction. If one pole is held adjacent a pole piece, weaker currents of excellent quality but less value are produced.

It is obvious that the invention may be embodied in many forms and constructions, and I wish it to be understood that the particular forms shown are but a few of many forms. Various modifications and changes being possible, I do not limit myself in any way with respect thereto.

What is claimed is:

1. An electric pickup for phonograph records and the like comprising, a stationary magnet system having fixed, spaced apart poles, a stylus operated vibratory member having magnetizable material carried between the poles but out of contact therewith, a coil, and a magnetizable core 85 in the coil, the core and coil being housed within the magnet of the magnet system with the tip of the core adjacent the vibratory magnetizable material and out of contact therewith.

2. An electric pickup for phonograph records and the like, comprising, a stationary magnet system including a horse shoe magnet and having fixed, spaced apart poles, a vibratory armature member having magnetizable material carried between the poles but out of contact therewith and rigidly connected to a stylus to be actuated thereby between the poles, a coil, and a magnetizable core in the coil, the tip of the core 95 being adjacent the vibratory magnetizable material and out of contact therewith, the core being disposed relative to the magnet system such that it normally receives substantially no flux therefrom.

3. An electrical pickup for phonograph records and the like, comprising a stationary magnet system having fixed, spaced apart poles, a stylus fastened to a stylus carrier, a support on which the stylus carrier is pivotally mounted, the stylus carrier being provided with a magnetizable armature disposed between the poles and adapted to be vibrated back and forth in the air gap, a magnetizable core adjacent the armature 115 and adapted to receive a varying flux according to the position of the armature, and a current generating coil wound about the core.

4. An electrical pickup for phonograph records and the like, comprising a stationary magnet system having fixed, spaced apart poles, a stylus fastened to a stylus carrier, a support on which the stylus carrier is pivotally mounted, the stylus carrier being pro-

vided with a magnetizable armature disposed between the poles and adapted to be vibrated back and forth in the air gap, a magnetizable core adjacent the armature and adapted to receive a varying flux according to the position of the armature, and a current generating coil wound about the core, the core and coil being housed within the magnet system parts with the core in the neutral zone thereof.

5. An electrical pickup for phonograph records and the like, comprising a stationary magnet system having pole tips spaced apart to provide a narrow air gap, a stationary core having one end adjacent the pole tips, an armature provided with magnetizable material disposed in the air gap and being close to the poles and the tip of the core, a pivotal mounting for the armature to permit it to move back and forth in the air gap, a stylus bar rigidly connected to the armature and to a stylus, the pivotal mounting being substantially equidistant from the armature and stylus, and a coil about the core in which currents are generated by vibrations imparted to the stylus.

6. An electrical pickup for phonograph records and the like, comprising a current generating coil, a core for the coil, and a stylus bar carrying a vibratory armature movable relative to the end of the core and relative to fixed magnet poles to vary the flux through the core, the core normally receiving substantially no magnetic flux from the magnet poles, and a stylus for vibrating the armature.

7. An electrical pickup for phonograph records and the like, comprising a current generating coil wound about a magnetizable core, a magnetic system including a vibratory armature operable by and directly connected with a stylus to generate currents in the coil, means for pivotally supporting the stylus and armature so that they are movable in either direction from a neutral point with equal facility, and resilient means to hold the armature out of contact with the stationary parts of the magnet system.

8. An electrical pickup for phonograph records and the like, comprising a current generating coil wound about a core, a magnetic system including a vibratory armature operable by and directly connected with a stylus to generate currents in the coil, means for pivotally supporting the stylus and armature so that they are movable in either direction from a neutral point with equal facility, and resilient means to hold the armature out of contact with the stationary parts of the magnet system, the core and coil being mounted inside the magnet of the magnet system with the core substantially in the neutral zone of the same.

9. An electrical pickup for phonograph records and the like, comprising a support,

a permanent magnet carried thereby, the magnet having spaced pole tips adapted to accommodate an armature, a coil mounted between the side members of the magnet and having a core adjacent the pole tips and in the neutral zone of the magnet, and a stylus operated vibratory armature operating in the gap between the pole tips and in the gap between the pole tips and the core tip, and acting to vary the flux distribution in the core according to the position of the armature in the gap.

10. An electrical pickup for phonograph records and the like, comprising a support, a permanent magnet carried thereby, the magnet having spaced pole tips adapted to accommodate an armature, a coil mounted between the side members of the magnet and having a core adjacent the pole tips and in the neutral zone of the magnet, and a stylus operated vibratory armature operating in the gap between the pole tips and in the gap between the pole tips and the core tip, and acting to vary the flux distribution in the core according to the position of the armature in the gap, the gaps between the pole tips and core tip being greater than the gaps between the pole tips and the armature.

11. An electrical pickup for phonograph records and the like, comprising a stationary magnet, a current generating coil wound about a fixed core, the core and coil being mounted between the side members of the magnet, and a stylus operated vibratory armature in the magnet field and adjacent the core, the core normally receiving no flux from the magnet but receiving varying flux according to the position of the armature when operated by the stylus whereby currents are generated in the coil.

12. An electrical pickup for phonograph records and the like, comprising a support, a magnet carried thereby, pole pieces for the magnet separated to accommodate an armature, a stylus bar carrying a stylus at one end and an armature at the other end, the support having bearings for the stylus bar to carry the armature in the gap and permit it to move longitudinally of the gap, a magnetizable core close to the armature and adapted to be magnetized according to the position of the armature, and a current generating coil about the core.

13. An electrical pickup for phonograph records and the like, comprising a support, a magnet carried thereby, pole pieces for the magnet separated to accommodate an armature, a stylus bar carrying a stylus at one end and an armature at the other end, the support having bearings for the stylus bar to carry the armature in the gap and permit it to move longitudinally of the gap, a magnetizable core close to the armature and adapted to be magnetized according to

the position of the armature, a current generating coil about the core, and adjustable yieldable stops engageable with the stylus bar and acting to keep the armature out of 5 contact with the magnet.

14. An electrical pickup for phonograph records and the like, comprising a support, a stylus bar pivoted therein, a stylus carried by one end of the bar and an armature 10 at the other end, a magnet carried by the support and having pole pieces close to the armature and on opposite sides thereof, a coil carried by the support, a stationary core in the coil, the tip of the core having 15 a gap to receive the armature, and resilient stop means to hold the armature spaced from the core tip and pole tips whereby substantially no flux is induced lengthwise of the core.

20 15. An electrical pickup for phonograph records and the like, comprising a support, a stylus bar pivoted therein, a stylus carried by one end of the bar and an armature at the other end, the stylus and armature being substantially equidistant from the pivot point, a magnet carried by the support and having pole pieces close to the armature and on opposite sides thereof, a coil carried by the support, a stationary 25 core in the coil, the tip of the core having a gap to receive the armature, and resilient stop means to hold the armature spaced from the core tip and pole tips whereby substantially no flux is induced lengthwise of the core.

30 16. An electrical pickup for phonograph records and the like, having a magnet with closely spaced pole tips, a vibratory armature therebetween, a coil housed within the 35 magnet and having a magnetizable core projecting therefrom with its tip adjacent the armature.

40 17. An electrical pickup for phonograph records and the like, comprising a support having a bearing at the lower end, a stylus bar pivoted in the bearing for vibration about one fixed axis, a stylus carried at one end of the bar and an armature at the other end, a magnet carried by the support and 45 having pole tips close to the armature and on opposite sides thereof, the armature being movable in the air gap to change the flux distribution between the pole tips and projecting beyond the pole tips, a stationary 50 coil carried by the support, and a stationary core for the coil, the end of the core being disposed adjacent the armature and substantially spaced from the pole tips, whereby substantially no flux is induced length- 55 wise of the core when the armature is in neutral position.

60 18. An electrical pickup for phonograph records and the like, comprising a support having a bearing at the lower end, a stylus 65 bar pivoted in the bearing for vibration

about one fixed axis, a stylus carried at one end of the bar and an armature at the other end, a magnet carried by the support and having pole tips close to the armature and on opposite sides thereof, the lines of flux 70 between the poles being in the direction of motion of the armature, the armature being movable in the air gap to vary its distance from the pole tips whereby one pole or the other predominates, the armature projecting 75 beyond the pole tips, a stationary coil carried by the support, and a stationary core for the coil, the end of the core being disposed adjacent the armature and substantially spaced from the pole tips, whereby 80 substantially no flux is induced lengthwise of the core when the armature is in neutral position.

19. An electrical pickup for phonograph records and the like, comprising a support having a bearing at the lower end, a stylus bar pivoted in the bearing for vibration about one fixed axis, a stylus carried at one end of the bar and an armature at the other end, a horseshoe magnet carried by the support and having pole tips close to the armature and on opposite sides thereof, the armature being movable in the air gap to change the flux distribution between the pole tips and projecting beyond the pole tips, a stationary coil carried by the support, and a stationary core for the coil, the end of the core being disposed adjacent the armature and substantially spaced from the pole tips, whereby substantially no flux is induced 90 lengthwise of the core when the armature is in neutral position, the coil and core being mounted between the sides of the horseshoe magnet.

20. An electrical pickup for phonograph records and the like, comprising a support having a bearing at the lower end, a stylus bar pivoted in the bearing for vibration about one fixed axis, a stylus carried at one end of the bar and an armature at the other end, a horseshoe magnet carried by the support and having pole tips close to the armature and on opposite sides thereof, the armature being movable in the air gap to change the flux distribution between the pole tips and projecting beyond the pole tips, a stationary coil carried by the support, and a stationary core for the coil, the end of the core being disposed adjacent the armature and substantially spaced from the pole tips, whereby substantially no flux is induced 100 lengthwise of the core when the armature is in neutral position, the coil and core being mounted between the sides of the horseshoe magnet.

21. An electrical pickup for phonograph records and the like, comprising a support having a bearing at the lower end, a stylus 110

bar pivoted in the bearing for vibration about one fixed axis, a stylus carried at one end of the bar and an armature at the other end, a magnet carried by the support and 5 having pole tips close to the armature and on opposite sides thereof, the armature being movable in the air gap to vary its distance from the pole tips and projecting beyond the pole tips, a stationary coil carried 10 by the support, a stationary core for the coil, the end of the core being disposed adjacent the armature and substantially spaced from the pole tips, whereby substantially no flux is induced lengthwise of the core when the 15 armature is in neutral position, and adjustable, yieldable stops cooperating with the stylus bar to prevent contact of the armature with the pole tips.

22. An electrical pickup for phonograph records and the like, comprising a support having a bearing at the lower end, a stylus bar pivoted in the bearing for vibration about one fixed axis, a stylus carried at one end of the bar and an armature at the other 20 end, a magnet carried by the support and having pole tips close to the armature and on opposite sides thereof, the armature being movable in the air gap to vary its distance from the pole tips and projecting beyond the pole tips, a stationary coil carried 25 by the support, a stationary core for the coil, the end of the core being disposed adjacent the armature and having a longitudinally extending armature receiving slot, the core 30 being substantially spaced from the pole tips, whereby substantially no flux is induced lengthwise of the core when the armature is in neutral position.

23. An electrical pickup adapted for use 40 with lateral cut phonograph records and the like, comprising a support, a stylus bar pivoted therein to move back and forth under the control of the record groove, an armature carried by the bar opposite the 45 pivot and partaking of lateral motion of sound character, a stationary core and current generating coil the axis of which are approximately in line with the axis of the stylus bar, and a magnet system having 50 poles on opposite sides of the armature.

WALTER H. SCHIMPF.
